UNITED STATES PATENT OFFICE.

WALTER M. DANN, OF WILKINSBURG, PENNSYLVANIA, ASSIGNOR TO WESTINGHOUSE ELECTRIC AND MANUFACTURING COMPANY, A CORPORATION OF PENNSYLVANIA.

TRANSFORMER-TANK.

1,374,553.

Specification of Letters Patent. Patented Apr. 12, 1921.

Application filed February 18, 1915. Serial No. 8,997.

To all whom it may concern:

Be it known that I, WALTER M. DANN, a citizen of the United States, and a resident of Wilkinsburg, in the county of Allegheny and State of Pennsylvania, have invented a new and useful Improvement in Transformer-Tanks, of which the following is a specification.

My invention relates to inclosed electrical apparatus, and it has special reference to casings in which electrical devices, such as alternating current transformers, may be contained.

More particularly, my invention relates to the construction of the heat-radiating means for such casings whereby adequate heat radiation is insured for the electrical apparatus contained in the casings.

It is usual to immerse electrical devices, and especially power transformers, in insulating and cooling fluids which are contained in suitable casings. Inasmuch as the cooling fluid is utilized to absorb the heat generated in the electrical apparatus, it is desirable to provide means for effectively dissipating the heat so absorbed. To this end, a transformer casing has been invented, as disclosed in Patent No. 913,060 to Otto Schaumberg and assigned to the Westinghouse Electric & Manufacturing Company, in which a very large heat-radiating surface is secured by providing a very large number of cylindrical tubes of relatively small diameter so disposed as to establish communication between the upper and the lower portions of a tank. The heat generated in the transformer establishes a circulation of the cooling and insulating fluid through the body portion or tank of the casing in one direction and

through the cylindrical tubes in the other direction, since the large heat-radiating surfaces of the tubes tend to keep the liquid in the tubes at a lower temperature than that obtaining in the body of liquid which is in proximity to the transformer or heat-generating apparatus.

However, a transformer casing which is provided with cylindrical tubes or pipes and constructed in accordance with the above-mentioned description is expensive to manufacture because of the large number of pipes or tubes necessary for furnishing an adequate radiating surface. In order to decrease the cost of manufacture of such a casing, I propose heat radiators of an improved

type whereby a large radiating surface for the casing may be obtained, while, at the same time, a relatively small number of exterior passageways between the upper and lower portions of the casing is required.

60

Heretofore, it has been substantially impossible to provide a cheap transformer casing of the external tubular type which could be employed with high power-capacity transformers to provide adequate cooling means and would be light in weight and insured against the development of faulty leaks, as well as be strong enough mechanically to permit transformers of large size to be contained therein. Again it is highly desirable to provide such a casing in which the transformer may be shipped in oil. To these ends I have provided the present transformer casing, but other objects of my invention will be clearly pointed out in the following specification.

65

For a better understanding of the characteristic features, the nature, and the scope of my invention, reference may be had to the following description and the accompanying drawing in which Figure 1 is a view, partially in elevation and partially in section, of a transformer and an inclosing casing therefor which is constructed in accordance with my invention; Fig. 2 is a plan view, partially in section, of a form of my radiators, Fig. 3 is an enlarged side view of a portion of the heat radiator shown in Fig. 2, and Fig. 4 is a figure by means of which I propose to demonstrate the advantages of a preferred form of my radiator as shown in Figs. 2 and 3.

70

Referring to Fig. 1, a transformer 1 having a magnetizable core member 2, a supporting frame 3 therefor, and a winding 4 inclosed in a fluid-containing casing. Terminal bushings 6 provide means for electrically connecting the transformer windings 4 to exterior circuits that are utilized for electric power distribution.

75

The casing 5, as shown, comprises a cylindrical sheet steel shell or tank 7 which is secured to a base 8 and provided with a crown 9. Tubular portions 10, 10', 11 and 11', extending into the upper and lower portions, respectively, of the transformer casing 5, are secured to the tank 7 and to heat radiators 12 which establish communication between the upper and lower portions of the casing 5. The transformer 1 is im-

110

mersed in a body 13 of insulating fluid, the upper level of which extends above the tubular portion 10 and 10'. As heat is generated in the transformer 1, the cooling fluid 13 absorbs and subsequently radiates it by reason of its circulation through the heat radiators 12. It is apparent that, as the cooling fluid within the main body portion of the casing 5 becomes heated, it will rise 10 upwardly and pass downwardly through the heat radiators 12. Inasmuch as the heat radiators 12 contain relatively large quantities of insulating fluid, each must be provided with adequate and effective heat- 15 radiating surface. At the same time, the heat radiators 12 must permit a free and unobstructed flow of the cooling fluid 13 therethrough.

A preferred form of my heat radiator, as 20 shown in Figs. 2 and 3, comprises front and side walls 14, preferably made from thin sheets of steel which are provided with spaced lenticular portions or longitudinal corrugations. To lend rigidity to the structure, I provide in the form shown, a reinforcing plate 15 that bridges opposite side walls 14 of the radiators and to which it is secured by water-tight or continuous autogenous joints. Top and bottom end plates 30 16, which conform preferably to the shape of the cross sections of the top and bottom of the radiators 12, are secured to the edges of the walls 14 and the plate 15 in the usual manner. It will be noted that, by spreading 35 the side walls 14 in substantially a V-shape, by reason of employing the plate 15, the passageways 17 extending between oppositely-disposed reentrant portions 18 are so proportioned that a substantially negligible 40 frictional resistance is offered to the flow therethrough of the cooling fluid 13.

The advantage of this type of construction will be apparent by referring to Fig. 4 in which a corrugated sheet steel member 45 19 is shown and from which I prefer to form the walls 14 of my heat radiators 12. By bending the plate 19 to a shape which conforms to the dotted line 20, an intermediate corrugation 21 is flattened out to form a 50 wall 22 which constitutes the blunt apex of the chamber thus provided. If no rear plate, as shown at 15 in Fig. 2, is furnished to spread the side walls 14 in a substantially V-shape, passageways 23 between oppositely-disposed reentrant portions 24 will be the 55 same size and entirely too small to permit circulation of the cooling fluid 13 through the heat radiators without offering undue frictional resistance. Inasmuch as the rate 60 at which the fluid 13 will circulate is affected by the temperature difference between the fluid at the top of the radiator 12 and the fluid at the bottom of the radiator, it is desirable to offer as little frictional resistance 65 as possible to the flow of the fluid in order

that the heat occasioned by this temperature difference may be employed to substantially its full value for circulating purposes. When the passageways 23 are small and have the same dimensions, as shown in Fig. 4, 70 the frictional resistance offered to the circulation of the fluid 13 is considerable, and the rate of flow of this fluid is substantially retarded. By providing the series of passageways 17 as shown in Fig. 2, in which 75 the passageways adjacent to the reinforcing plate 15 are much larger than the passageways more remote therefrom, the frictional resistance offered to the flow of the fluid will be decreased. A larger portion of the fluid 80 13, as it circulates through the radiators 12, tends to flow through the opening 17 which is closest to the inlet 10 of the radiator. Increasingly smaller quantities of the fluid 85 will flow through those openings 17 which are more remote from the reinforcing plate 15. In this manner, the frictional resistance offered by the radiators 12 to the circulation of the cooling fluid is minimized, thereby increasing the mean rate of circulation of the 90 cooling fluid.

It is sometimes desirable to detach the radiators 12 from the tank 7 to facilitate in the handling or shipping of the transformer and the casing, and, to this end, the radiators are provided with the tubular portions 95 10 and 11 which have flanged portions 25 that are drilled to receive tie-bolts 26. Similarly, the shell portion or tank 7 of the casing is provided with corresponding tubular portions 10' and 11' which have flanges 27 that are correspondingly drilled to receive likewise the bolts 26. By means of these bolts, the radiators are secured firmly to the shell portion of the casing and, at the same 100 time, may be externally and expeditiously detached therefrom. In this manner, the openings in the radiators register with the openings in the upper and lower portions of the tank, thereby permitting the insulating 110 and cooling liquid 13 to circulate therethrough substantially unobstructedly, as is desired. Of course, any suitable washers, filling, etc. may be employed to make the clamp joints tight between the cooperatively 115 engaged tubular portions. While I have shown in detail in Fig. 2 the method which I have employed in attaching the radiators 12 to the tank, it will be apparent that many other methods of construction may be substituted 120 for the one shown which will be satisfactory. Frequently, it may be unnecessary to detach the radiators from the casing, and, in this instance, they may be welded directly to the shell portion 7 by means of simple cylindrical pipes. While the tubular portions 10, 10', 11 and 11' may be welded to their respective members, I have shown the tubular portions 10' and 11' riveted to the tank 125 so as to provide a strong reinforcing struc- 130

ture to support the outwardly projecting radiators 12. The top plate 16 of each radiator is provided with a removable plug 28 which, on being opened, permits the air to 5 be expelled from the radiator when the casing is being filled with oil. By this means, all the radiators may be completely filled with oil.

As above mentioned, the end plates 16, 10 which are secured to the walls 14 of the radiators 12, conform to the shape of the cross section of the bottom and top portions of the radiators in order that all of the exterior surfaces of the radiators may be utilized to 15 their fullest extent in effectively radiating the heat absorbed by the cooling fluid. To explain further, all of the exposed surfaces of the corrugations are in direct contact with the air currents sweeping upwardly along 20 the radiators. If the end plates 16 projected outwardly and across the spaces between adjacent corrugations so as to obstruct the free movement of the air currents near the end portions of the radiators, the air currents would be deflected at the end portions 25 and, therefore, not come into contact with all of the exterior surfaces of the radiators. To this end, the corrugations of the radiators project beyond the end plates 16 in order 30 that their entire surfaces may be exposed to the upwardly sweeping air currents. By thus effectively utilizing all of the exterior surfaces of the radiators 12 for dissipating the heat absorbed by the cooling fluid 13, a 35 very efficient radiator is provided.

In order to preclude the development of leaks resulting from faulty joints, which would be the case if the end plates 16 were cut so as to conform to all of the corrugations provided in the radiators and subsequently welded thereto, I construct my radiators as shown in Fig. 2. At the upper and lower portions of the radiators, the adjacent walls comprising the corrugations 14 are pressed together, as shown at 29, and then welded together to provide continuous autogenous joints. By this form of construction, each corrugation terminates at both ends in solid fins which are perpendicular to the walls of the radiators. The end plates 16 are then cut substantially in a V shape, and welded to continuous straight edges 30, which greatly facilitates the welding operation and, at the same time, insures 40 tight joints. It will be observed that the larger portion of the heat radiating surface of each of the radiators 12 is made up of a plurality of opposed heat radiating surfaces that are spaced from one another. In the 50 radiators shown, these opposed and spaced heat radiating surfaces are of lenticular form and are spaced in directions substantially normal to the walls of the tank. In other words, the corrugations are the equivalent of a plurality of spaced and opposed

radiating surfaces of lenticular form that are approximately parallel to the portions of the walls of the tank that are subtended by said corrugations. Since the larger portion of the heat radiating surface of each radiator comprises the opposed surfaces that are spaced from one another in directions substantially normal to the walls of the tank, a large effective radiating surface for the casing is secured without increasing the size 75 of the tank or spacing the radiators too close to one another. As a consequence, an improved circulation of air currents that sweep the heat radiating surface of the casing is obtained. Since the opposed and spaced 80 radiating surfaces extend substantially throughout the entire length of the tank, a very large effective radiating area is provided by each radiator.

It will be noted that each radiator 12 85 separately communicates with the tank at its top and bottom. Moreover, each radiator may be separately detached from the tank without disturbing any of the remaining radiators.

While I have shown and described in detail one embodiment of my invention, I do not desire that my invention be restricted to any special type of construction, inasmuch as many modifications may be made 95 without departing from the spirit and scope of the appended claims. This application is a continuation in part of my patent application, Serial No. 2839, filed Jan. 18, 1915, and assigned to the Westinghouse Electric 100 & Manufacturing Company.

I claim as my invention:

1. A liquid containing casing having a plurality of detachable heat radiators which connect its end portions and provide 105 closed paths for the circulation of a body of liquid, the radiators comprising chambers having side-walls in which are formed longitudinally extending corrugations and end plates therefor which conform in shape to 110 the cross sections of the end of said chambers in order to subject substantially all the exterior side-wall surfaces of the radiators to rising air currents.

2. A liquid containing casing having a 115 body portion and a plurality of heat radiators located outside the body portion and extending longitudinally thereof in order to connect its end portions and to provide a closed path for the circulation of a body of 120 liquid therethrough, each of said radiators comprising a hollow corrugated sheet metal member of triangular cross section, the side of the radiator constituting the base of the triangle being disposed adjacent to said body portion of the casing and having openings at its end portions to permit ingress and egress of the liquid.

3. A liquid containing casing having a 125 tank, a plurality of hollow exteriorly de- 130

- tachable heat radiators separately attached to, and communicating at their end portions with said tank, each of said radiators comprising a sheet metal member having a substantially triangular shaped cross section and longitudinally extending lenticular portions formed therein, and end members that conform to the shape of the cross section of said sheet metal member, the side of the radiator constituting the base of the triangle being placed adjacent to said tank.
4. The combination with a liquid-containing casing for a heat-generating device, of a heat radiator therefor which communicates with said casing and comprises side walls made of a strip of sheet metal and provided with longitudinal corrugations, and a reinforcing plate which spreads said side walls apart in substantially a V-shape, said plate being secured to said side walls by continuous autogenous joints.
5. The combination with a liquid-containing casing for a heat-generating device, of a heat radiator which communicates with said casing and comprises a corrugated sheet metal member which is bent in substantially a V-shape, one of the corrugations thereof being expanded to constitute a blunt apex for the V, and a plate extending between adjacent sides of the sheet metal member to form a substantially triangular shaped chamber.
6. The combination with a liquid-containing casing, of a detachable heat radiator therefor comprising a corrugated sheet metallic member which is bent in substantially a V-shape, one of the corrugations being expanded to constitute a blunt apex for the V, a plate bridging adjacent legs of the V and secured thereto by continuous autogenous joints, bottom and top end members conforming in shape with, and secured to the corrugated member, and tubular members disposed adjacent to said top and bottom end members to provide means of ingress and egress for the liquid contained in said casing.
7. A containing casing having a body portion and a plurality of exteriorly detachable and hollow heat radiators extending longitudinally thereof and connecting its end portions for permitting the circulation therethrough of a body of liquid contained in said casing, the radiators comprising hollow members, those sides of which are parallel to the sides of said casing having relatively smaller dimensions than the dimensions of the other sides of said hollow members.
8. A containing casing having a body portion and a plurality of exterior and hollow heat radiators extending longitudinally thereof and connecting its end portions to permit the circulation therethrough of a body of liquid contained in said casing, the radiators comprising hollow chambers having longitudinally corrugated sheet metal sides and end members therefor which are formed to maintain the spaces between adjacent corrugations unobstructed throughout the entire length of the radiators.
9. The combination with a device to be cooled, a fluid in which the device is immersed, and a tank containing the device and the fluid, of a plurality of radiators detachably secured to the exterior of the tank each of which communicates separately with the tank at its top and bottom.
10. The combination with a device to be cooled, a fluid in which the device is immersed, and a tank containing the device and the fluid, of a plurality of separately detachable flat and elongated radiators secured to the exterior of the tank and having their longer axes respectively extending longitudinally and radially with respect to the tank.
11. The combination with a device to be cooled, a fluid in which the device is immersed, a tank containing the device and the fluid and having lateral outlet and inlet openings near its top and bottom, and flanges attached to the tank and surrounding the said openings, of radiators exterior to the tank each of which is provided with an inlet and an outlet, flanges secured to the said inlets and outlets of the radiators, and means for clamping the latter flanges to the former.
12. The combination with a device to be cooled, a fluid in which the device is immersed, a tank containing the device and the fluid and having lateral outlet and inlet openings near its top and bottom, and flanges attached to the tank and surrounding the said openings, of radiators exterior to and extending longitudinally substantially from top to bottom of the tank each radiator having an inlet and an outlet, flanges attached to the said inlets and outlets of the radiators, and means for clamping the latter flanges to the former.
13. The combination with a device to be cooled, a fluid in which the device is immersed, and a tank containing the device and the fluid, of a plurality of radiators separately and detachably secured to the exterior of the tank and each of which communicates separately with the tank at its top and bottom.
14. The combination with a device to be cooled, a fluid in which said device is immersed, and a tank containing said device and said fluid and having flanged openings near the top and bottom, of a plurality of radiator units detachably secured to said tank and having flanged members at the top and bottom which are adapted to register with, and be secured to, the flanges surrounding said tank openings, whereby the

entire weight of each radiator unit is supported by the means which admit of fluid communication between said unit and said tank.

- 5 15. The combination with a device to be cooled, a fluid in which said device is immersed, and a tank containing said device and said fluid and having flanged openings near the top and bottom, of a plurality of
10 radiator units detachably secured to said tank and having flanged members at the top and bottom which are adapted to register with, and be secured to, the flanges surrounding said tank openings, whereby
15 the entire weight of each radiator unit is

supported by the means which admit of fluid communication between said unit and said tank, the vertical dimension of the radiating surface of each of said units being substantially the same as the distance between the upper and lower openings in said tank. 20

In testimony whereof, I have hereunto subscribed my name this 17th day of Feb., 1915.
